UNITED STATES PATENT OFFICE.

THOMAS DOWMAN, OF CHESTER, ILLINOIS.

LOCK.

SPECIFICATION forming part of Letters Patent No. 595,290, dated December 14, 1897.

Application filed November 23, 1896. Serial No. 613,165. (No model.)

To all whom it may concern:

Be it known that I, THOMAS DOWMAN, a citizen of the United States, residing at Chester, in the county of Randolph and State of Illinois, have invented certain new and useful Improvements in Door-Locks; and I do hereby declare the following to be a full, clear, and exact description of the invention, such as will enable others skilled in the art to which it app pertains to make and use the same.

This invention relates to improvements in locks, and has more particular relation to lock attachments for securing the bolt in its shot position.

15 The invention consists of certain novel constructions, combinations, and arrangements of parts, all of which will be hereinafter more particularly set forth and claimed.

In the accompanying drawings, forming 20 part of this specification, Figure 1 represents a side elevation of a door provided with my improved bolt-lock attachment, the position of the bolt being shown in dotted lines, and the locking-plunger being in its withdrawn position.

25 Fig. 2 represents a broken central vertical section through said door on the line of my said improved bolt-locking device, the plunger being in its operative position within the bolt. Fig. 3 represents a similar view

30 with the plunger withdrawn into its inoperative position. Fig. 4 represents an end elevation of the door with a modified form of my attachment applied thereto, a portion of the same being shown in section; and Fig. 5 represents a similar view to Fig. 4 of another form 35 of my invention.

In the drawings represents the door, B the lock-bolt, and C my improved bolt-locking attachment. Said attachment comprises a casing c, adapted to be secured to the inside of a door, and a plunger c', locking in said casing. A coil-spring c² surrounds said plunger and bears with one end against the lateral pin c³, mounted in said plunger and with its 40 opposite end against an annular flange c⁴, formed about the mouth of the aperture through the casing C. An operating-handle c', provided with a circular bifurcated head c⁶, is pivoted eccentrically about the upper 45 end of said plunger c' by means of a pivot-pin c⁷. A suitable aperture is formed through the

door to permit the plunger c' to reach the bolt B and enter a suitable aperture cut therein to lock it in its shot position.

It will be observed from the foregoing description that when the handle c⁵ is turned in the position shown in Fig. 2 the plunger c' will be released and forced inward to engage the aperture in the bolt B by means of the coil-spring c². When said handle c⁵ is rotated, 55 the periphery of the circular portion c⁶ will engage the flange c⁴ and withdraw the plunger c' from the bolt and hold it in said withdrawn position. It will be observed that by this means after the bolt B has been once 60 shot and the plunger c' allowed to project inward, so as to engage the aperture therein, said bolt cannot be withdrawn or unlocked, either by a key from without or any other means, until the said plunger has first been 65 withdrawn. By this peculiar construction the lock is made practically burglar-proof, as no instrument from the outside of the door can reach and turn the handle c⁵ up, so as to withdraw the plunger.

In the modified form of my invention shown in Fig. 4 the construction is substantially the same, with the exception that the plunger is provided at its outer end with a head c⁹, having a semicircular portion c¹⁰. A semicircular projection c¹¹ is formed on the outer end of the casing, so that when said head c⁹ is pulled out and rotated the projection c¹⁰ will occupy a position above the projection c¹¹ and thus prevent the plunger from entering it again 80 until the head c⁹ is again rotated to bring the said projections into the same horizontal plane. In all other respects this modified construction of my invention is substantially 85 the same as that hereinbefore described.

90 My said improved lock-fastener may be applied to ordinary locks now in use, in which the bolt is provided with a recess or slot capable of receiving the plunger c'.

In the construction shown in Fig. 5 the 95 outer end of the casing is provided with two grooves f f, arranged upon diametrically opposite sides and adapted to receive the ends of a T-handled plunger f'. When this plunger is withdrawn and turned, the arms at the 100 end of the same lie against the outer end of the casing at right angles to the grooves f f.

Having thus described my invention, what I claim as new, and desire to secure by Letters Patent, is—

1. In a lock-fastening device, the combination with a suitable casing, of a plunger mounted therein and provided with a washer rigidly mounted thereon, a coil-spring surrounding said plunger and bearing with one end against said washer and the opposite end 10 against the end of the casing so as to normally force the plunger forward to engage a suitable aperture formed in the bolt, an operating-lever mounted on the protruding end of the plunger and adapted to engage the casing to withdraw said bolt against the tension of the spring, substantially as described.
2. In a lock-fastening device, the combination with a suitable attaching-casing, of a plunger mounted in the same and adapted to 20 project through the door into a suitable aperture formed in the bolt, a spring connecting said plunger and casing for normally projecting the former into the aperture of the bolt, and a handle having a circular enlargement 25 and eccentrically pivoted upon the outer end of said plunger so that its periphery engages the outer end of the casing and withdraws the plunger therefrom against the tension of the spring, substantially as described.
3. In a lock-fastening device, the combination with a suitable casing, of a plunger mounted therein and adapted to project 30

through the door into a suitable aperture formed in the bolt, a coil-spring surrounding said plunger and forcing the same normally 35 inward, and an operating-handle having a circular enlargement and eccentrically pivoted upon the outer end of said plunger so that its periphery engages the outer end of the casing to withdraw the plunger therefrom 40 against the tension of the spring, substantially as described.

4. In a lock-fastening device, the combination with a suitable attaching-casing, of a spring-pressed plunger mounted in the same 45 and adapted to project through the door into a suitable aperture formed in the locking-bolt, and an operating-handle having a circular bifurcated head that is eccentrically pivoted upon the outer end of said plunger-rod 50 so that the respective peripheries of said bifurcated portion engage the outer end of the casing upon each side of the plunger-rod to withdraw the latter from the casing against the tension of its spring, substantially as described.

In testimony whereof I have signed this specification in the presence of two subscribing witnesses.

THOMAS DOWMAN.
